JOGGLE DIE

Elbridge W. Hall, San Diego, Calif.

Application September 16, 1946, Serial No. 697,339

10 Claims. (Cl. 153—25)

1

My invention relates to a joggle die, more particularly for use in sheet metal forming, and the objects of my invention are:

First, to provide a die of this class which is quickly adjustable for depth of joggle without changing the fixed relationship of the dies in connection with the press to which they are secured;

Second, to provide a joggle die of this class which is provided with quickly changeable inserts, adapted to fit the contour or shape of various parts to be joggled therein;

Third, to provide a joggle die of this class having inserts in which various radii are meshed to fit and form a smooth pressure surface at the joggle break in metal of various gauges;

Fourth, to provide a joggle die of this class in which depth adjustment of the joggle may be made with stepped-up blocks or shims;

Fifth, to provide a joggle die of this class which lends itself to mass production of sheet metal parts to be joggled; and

Sixth, to provide a joggle die of this class which is very simple and economical in construction, efficient in its action, and which will not readily deteriorate or get out of order.

With these and other objects in view, as will appear hereinafter, my invention consists of certain novel features of construction, combination and arrangement of parts and portions as will be hereinafter described in detail and particularly set forth in the appended claims, reference being had to the accompanying drawings and to the characters of reference thereon forming a part of this application in which:

Figure 1 is a side elevational view of my joggle die showing the male and female structure thereof in superimposed relationship ready for use in joggling parts; Figure 2 is a fragmentary top or plan view of the female structure of my joggle die taken from the line 2—2 of Fig. 1; Fig. 3 is a fragmentary bottom or plan view of the male structure of my joggle die; and Fig. 4 is a fragmentary sectional view taken from the line 4—4 of Fig. 1.

Similar characters of reference refer to similar parts and portions throughout the several views of the drawings.

The die holder 1, ways block 2, die holder 3, step blocks 4 and 5, offset blocks 6 and 7, forming dies 8, 9, 10 and 11, wiper plates 12, bolts 14 and 15, gibs 16 and 17, bolts 18 and 19, and the work holder constitute the principal parts and portions of my joggle die.

The die holder 1 is divided with a ways block engaging dovetail portions 1a slideably engaged

2 with the ways block 2 and fixed in position by the said screws 2a screw-threaded into the ways block 2. The die holder 1 is provided with a recessed portion 1b having an inclined surface 1c and a step surface 1d. Inwardly of the inclined surface 1c is a dovetailed slot 1e as shown in Fig. 4 of the drawing. Slideably positioned in the dovetailed slot 1e is the gib 16 in which the bolts 14 are screw-threadedly connected holding the offset blocks 6 in certain adjusted relationship with the inclined portion 1c. The step block 4 is provided with conforming step portions meshing with the step surface 1d of the die holder 1, all as shown best in Fig. 1 of the drawings. The forming dies 8 and 9 are provided with offset forming planes 8a and 9a arranged to conform to the offset planes 10a and 11a of the forming dies 10 and 11, it being noted that the forming dies 8 and 9 are connected to the die holder 1 and offset block 6 respectively. The forming dies 10 and 11 are connected with the offset block 7 and die holder 3 respectively. The die holder 3 is provided with a recessed portion 3a having a step surface 3b and inclined surface 3c therein supporting the step block 5 and offset block 7 respectively. The gib 17 is similar in construction to the gib 16 described in connection with the die holder 1 and the bolts 15 are similar to the bolts 14 all as shown best in Fig. 1 of the drawings. The wiper plate 12 is secured at the outer side of the forming die 8 and is provided with an angular wiper portion 12a at its inner side arranged to engage the work when forming the same. As shown in Fig. 4 of the drawings, the forming die 9 is provided with a radius forming lip 9b arranged to engage and maintain the form of an angular part when joggling the same. The forming die 11 arranged to cooperate with the forming die 9 is provided with an internally radius portion 11b arranged to support the inside of the part being joggled. The work holder 20 is secured in connection with the die holder 3 by a clamp bolt 20a and this work holder 20 is arranged to engage the outer side of the work for holding the same adjacent to the forming die 11 in proper alignment with the forming die 9. It will be noted that the forming dies 9 and 11 respectively are provided with dovetailed locking portions 9c and 11c which interlock in connection with the die holders 2 and 3 respectively. The offset blocks 6 and 7 are supported by the gibs 16 and 17 which are dovetailed gibs engaging slotted portions 1e and 3c in the die holders 1 and 3 respectively.

The operation of my joggle die is substantially as follows:

The work A as shown in Fig. 4 of the drawings

is clamped in connection with the forming die 11 by the work holder 20 secured to the die holder 3 by the bolts 20a. The ways block 2 and the bottom portion of the die holder 3 are secured in connection with the head and the anvil of a press respectively, and the die holder 1 is moved longitudinally of the ways block 2 in relationship to the die holder 3 for proper alignment of the forming dies 8 and 9 relatively to the forming dies 10 and 11 when set for a certain depth of joggle, dependent upon the spaced relation of the forming surfaces 8a and 9a of the forming dies 8 and 9, cooperating with the forming surfaces 10a and 11a of the forming dies 10 and 11 respectively. The depth of joggle may be set up by moving the step block 4 inwardly and outwardly on the step surface 1d permitting the abutted relationship therewith of the offset block 6 to be adjustably set by sliding the gib 16 in the dovetailed slotted portion 1e and then tightening the bolts 14. Adjustment of the offset block 7 in connection with the die holder 3 is accomplished in a similar manner by abutment thereof with the step block 5. When changing the depth of joggle by shifting the offset blocks 6 and 7, the die holder 1 must be adjustably shifted in connection with the ways block 2 by releasing the set screws 2a and resetting the same when proper setup of the die holders 2 and 3 is made. The work A when secured in connection with the forming die 11 as hereinbefore described is formed by a vertical movement of the die holder 1 toward the die holder 3 causing the forming die 9 to engage the upper portion of the work A, whereby the radius forming lip 9b of the forming die 9 maintains the smooth radius of the part while the offset relation of the forming dies 8 and 9 forms the part over the forming dies 10 and 11, creating an offset joggle therein equal to the difference in elevation of the forming surfaces 8a and 9a of the forming dies 8 and 9. It will be noted that the radius portion 9b conforms with the similar radius in the forming die 8 and that the wiper 12 engages the side of the part and forms the same into joggled condition without wrinkling of the material at the outer side thereof.

Various gauges of material may also be compensated for by adjustment of the dies 8 and 9 relatively to the dies 10 and 11. The dies 8 and 9 are slideably adjustable relatively to each other by means of interlocking slideways 9b as shown in Fig. 1 of the drawings whereby a smooth lip is produced on the material joggled thereby.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a joggle die of the class described, a pair of die holders movable relatively to each other, recessed portions in said die holders having stepped surfaces in a row inclined to the vertical therein and opposed inclined planes, offset blocks mounted on said inclined planes having horizontal surfaces, and step blocks engaging said offset blocks and said step surfaces of said recessed portions.

2. In a joggle die of the class described, a pair

of die holders movable relatively to each other, recessed portions in said die holders having stepped surfaces in a row inclined to the vertical therein and opposed inclined planes, offset blocks mounted on said inclined planes having horizontal surfaces, step blocks engaging said offset blocks and said step surfaces of said recessed portions, and forming dies in connection with said offset blocks at the horizontal surfaces and parallel thereto.

3. In a joggle die of the class described, a pair of die holders movable relatively to each other, recessed portions in said die holders having stepped surfaces in a row inclined to the vertical therein and opposed inclined planes, offset blocks mounted on said inclined planes having horizontal surfaces, step blocks engaging said offset blocks and said step surfaces of said recessed portions, forming dies in connection with said offset blocks, at the horizontal surfaces and parallel thereto, and second forming die in parallel offset relation to said first-mentioned forming die secured to said die holders longitudinally adjustable relatively to the other die holder.

4. In a joggle die of the class described, a pair of die holders movable relatively to each other, recessed portions in said die holders having stepped surfaces in a row inclined to the vertical therein and opposed inclined planes, offset blocks mounted on said inclined planes having horizontal surfaces, step blocks engaging said offset blocks and said step surfaces of said recessed portions, forming dies in connection with said offset blocks at the horizontal surfaces and parallel thereto, and second forming die in parallel offset relation to said first-mentioned forming die secured to said die holders longitudinally adjustable relatively to the other die holder, and a ways block secured to one of said die holders adapted to connect the same to a press.

5. In a joggle die of the class described, a pair of die holders movable relatively to each other, recessed portions in said die holders having stepped surfaces in a row inclined to the vertical therein and opposed inclined planes, offset blocks mounted on said inclined planes having horizontal surfaces, step blocks engaging said offset blocks and said step surfaces of said recessed portions, forming dies in connection with said offset blocks at the horizontal surfaces and parallel thereto, and a work holder in connection with one of said die holders adjacent to said forming dies and a wiper plate in connection with the other die holder in offset relation with said work holder adapted to wipe the outer sides of parts being formed by said first and second mentioned forming dies.

6. In a joggle die of the class described, a pair of die holders movable relatively to each other, recessed portions in said die holders having stepped surfaces in a row inclined to the vertical therein and opposed inclined planes, offset blocks mounted on said inclined planes having horizontal surfaces, step blocks engaging said offset blocks and said step surfaces of said recessed portions, and forming dies in connection with said offset blocks at the horizontal surfaces and parallel thereto; said first-mentioned and second-mentioned forming dies angularly slideably adjusted relative to each other for forming joggles of various depths.

7. In a joggle die of the class described, a pair of die holders movable relatively to each other, recessed portions in said die holders having

stepped surfaces in a row inclined to the vertical therein and opposed inclined planes, offset blocks mounted on said inclined planes having horizontal surfaces, step blocks engaging said offset blocks and said step surfaces of said recessed portions, and forming dies in connection with said offset blocks at the horizontal surfaces and parallel thereto; said first-mentioned and second-mentioned forming dies angularly slideably adjusted relative to each other for forming joggles of various depths; said die holders provided with dovetailed slotted portions and gibbs in said slotted portions in connection with said offset blocks.

8. In a joggle die of the class described, a pair of die holders movable relatively to each other, recessed wedging portions in said die holders, inclined planes adjacent thereto, offset blocks mounted on said inclined planes adjacent to said recessed wedging portions, and second blocks engageable with said offset blocks for maintaining the same in certain spaced relation with each other.

9. In a joggle die of the class described, a pair of die holders movable relatively to each other provided with recessed wedging portions having inclined planes parallel to each other, offset blocks mounted on said angular planes, and second blocks adjustably positioned longitudinally of

said inclined planes in said wedging recessed portions adapted to support said offset blocks in certain spaced relation to each other.

10. In a joggle die of the class described, a pair of die holders movable relatively to each other provided with recessed wedging portions having angular planes parallel to each other, offset blocks mounted on said inclined planes in said wedging portions, and second blocks adjustably positioned longitudinally of said inclined planes in said wedging portions adapted to support said offset blocks in certain spaced relation to each other, forming dies in connection with said offset blocks.
